DAVID E. ROSS, OF LA FAYETTE, INDIANA, ASSIGNOR TO ROSS GEAR & TOOL COMPANY, OF LA FAYETTE, INDIANA, A CORPORATION OF INDIANA

STEERING-GEAR-CONTROL LEVER ASSEMBLY

Application filed December 27, 1926. Serial No. 157,158.

This invention relates to control assemblies for use in connection with the steering gears of automobiles, the controls being mounted on the steering post above the hub of the steering wheel, so that the control levers can be readily operated by the finger or thumb of the operator while his hands are engaged with the steering wheel.

The invention provides simple and effective means for detachably attaching the several control levers to their respective control tubes in such manner as will permit levers and tubes of very thin cross-section to be used, and also permit the steering wheel to be removed from the steering post without having to disturb the nested control tubes or disconnect the steering gear.

The invention also provides novel means for mounting the horn button or other electrical signal circuit closing device upon the uppermost control lever of the assembly.

Other minor novel features of the invention will be hereinafter set forth.

The accompanying drawings illustrate practical embodiments of the invention, and I will describe the same with reference thereto to enable others familiar with the art to adopt and use the same; and summarize in the claims the essentials of the invention and novel features of construction and novel combinations of parts for all of which protection is desired.

In said drawings:—

Figure 1 is a vertical sectional view through one form of control assembly embodying my invention.

Fig. 2 is a similar view at right angles to the section shown in Fig. 1.

Fig. 3 is a detail view of one form of control lever and means for attaching same to its control tube.

Fig. 4 is a similar detail view of a modification of the lever.

Figs. 5, 5^a, and 5^b are respectively, a detail top plan, a longitudinal section, and a transverse section of a locking washer.

Figs. 6, 6^a, and 6^b are respectively, a detail top plan, a longitudinal section, and a transverse section of a control lever arm.

Fig. 7 is an enlarged detail section on the line 7—7 Fig. 4.

Fig. 8 is a vertical section, similar to Fig. 2 showing a modification of the construction of the upper control lever.

Figs. 9 and 9^a are respectively detail top and side views of the upper end of one of the control tubes, detached; and

Fig. 10 is an enlarged detail section on line 10—10 Figs. 3 and 4.

In the drawings the invention is illustrated as used in connection with a type of control assembly in general such as shown in my companion applications, filed December 15, 1926, Serial Nos. 154,922 and 154,923; but the present invention is not restricted to use with such control assemblies as it is readily adaptable to various others.

The operative parts of the control are usually mounted upon a stationary tube G which is customarily housed within the steering tube (not shown) to which the steering wheel is attached; the steering tube being usually rotatably mounted in an outer fixed column or casing. These features being old and well known, and not forming part of this invention are not illustrated. Within tube G are the nested control tubes C as usual. Each control tube C, may have very thin walls, and is provided at its upper end with preferably oppositely disposed integral lugs C⁴ which may be formed by slitting the metal of the tube and pressing the slit tongues outwardly to form lugs C⁴ as shown.

The distance between the outer extremities of the diametrically opposed lugs C⁴ of each control tube (Fig. 9) should be less than the inside diameter of the bore of the steering wheel and the nut by which the steering wheel (not shown) is secured to the steering tube, so that the said nut and wheel can be readily slipped over or on or off the ends of the nested tubes at will, so that the wheel can be put in or removed from position without disturbing the assembled control tubes.

On the upper end of the tube G is mounted a supporting member or yoke 1 which is adapted to carry the operative parts of the control assembly; said yoke being preferably constructed as described in my aforesaid ap-

lication Serial No. 154,923, and provided with an annular depending skirt 1^a.

Mounted upon the yoke 1 is a base member 2 which has an arcuate vertical flange portion 2^a extending through an arc of approximately 110 degrees, as described in my said application.

The control levers 4 are rotatably mounted axially of the yoke 1 and the arcuate portion 2^a of base member 2, three such levers being shown. Each control lever preferably has a handle 4^b and an annular portion 4^c slightly larger in interior diameter than the exterior diameter of the arcuate portion 2^a of base member 2. Each control lever is shown as provided with a radially disposed inwardly projecting arm which engages the control tube and such arm may be formed integral with the lever, as shown at 4^c in Fig. 3, or may be formed separately therefrom as shown at 4^d in Fig. 4, in which latter case the annular portion 4^c of the lever may be provided with a series of slots 4^e with any one of which the outer end of the arm 4^d can be detachably engaged.

Each arm (4^c or 4^d) has a circular head 4^h at its inner end provided with an axially disposed opening 4^k adapted to receive the upper end of its respective control tube, arranged axially of and within tube G.

The head 4^h of each lever arm is provided with slots 4^l (Fig. 6) corresponding in location to the lugs C⁴ on the control tube with which the head is to be engaged; these slots 35 permit the head 4^h to be freely slipped onto the tube C, the lugs C⁴ passing through the slots 4^l. The head 4^h is also provided with slots 4^m in its upper side corresponding in position to the lugs C⁴ on the related tube, 40 but disposed at an angle to the slots 4^l. The head is also preferably provided with threaded bores 4ⁿ for the engagement of screws 6^k by which a retainer or cap 6 is secured to the head as shown in Figs. 3, 4, 45 and 10.

The retainer 6 is shown as formed of a disk of metal conforming in size to the head, and said retainer is provided with inwardly projecting lugs 6^e which correspond in position with the slots C⁵ in the related control tube C, and with countersunk bores 6^m to register with the bores 4ⁿ in heads 4^h.

Preferably the slots 4^l in the head are slightly less in depth than the thickness of 55 the lugs C⁴, see Figs. 7 and 10, so that when the retainer is in place and the screws 6^k tightened, the control lever 4 is fixed securely against both rotatorial and longitudinal movement on the control tube C.

60 The control lever may be readily engaged with the control tube by slipping the head 4^h over the end of the related tube, the lugs C⁴ passing through the slots 4^l; then the control lever is turned until the lugs C⁴ register with the recesses 4^j in the head 4^h, and

the lever is raised until the lugs C⁴ are seated in the recesses 4^j; then the retainer 6 is applied over the head 4^h, its lugs 6^e engaging the slots C⁵ in the tube above the lugs C⁴; and then the screws 6^k are tightened securely 70 fastening the lever to the tube as shown.

The lugs C⁴ and 6^e provide a sufficiently large contact surface between the lever and tube to ensure turning of the tube by the lever. The countersunk ends of the openings 6^m in the register 6 are preferably roughened or serrated as indicated in Figs. 5 and 5^b, and the underside of the heads of screws 6^k are also preferably roughened or slightly serrated, so that the screws will not loosen when 80 tightened.

Three control levers are shown in the drawings, but obviously one or more than one may be used according to the number of control tubes employed.

It is desirable to provide an electric signal attachment or circuit closer at the top of the assembly. In the construction shown in Figs. 1 and 2 a cap piece 7 is attached to the base member 2 in any suitable manner, as by 90 screws 7^a. A button 8 is loosely confined within a central opening in the cap member 7; thus push button 8 may have a peripheral flange 8^b on its lower edge of larger diameter than the opening in the cap 7 to retain 100 the button in position in said opening.

The button 8 is supported upon the head 4^h of the upper control lever, which head is shown as of larger diameter than the heads of the underlying levers below it, but is detachably attachable to the related control tube in the manner above described. The hub or head 4^h of the upper lever (Figs. 1 and 2) may have an integral annular flange 4ⁿ adapted to coact with an annular depending flange 11^a on button 8.

The button 8 may be supported by a coiled spring 10 inserted between the button and the enlarged head 4^h on the hub of the upper control lever, said spring being preferably arranged exterior to the annular flange 4ⁿ and tends to hold the button in raised position. The button 8 may also be supported by an ordinary convolute electric push button spring 9 (Figs. 2 and 8) which is supported 115 on an insulating washer 11 mounted axially of the head 4^h within the annular flange 4ⁿ. The washer 11 has an aperture or slot 11^a for the passage of the bared end w of an electrical conductor W, which extends down 120 through the inner control tube C, and is attached to a metal contact piece 12 which is centered and retained in position on the insulating bushing 11 by a washer 13. The sides of spring 9 make electrical contact with the flange 4ⁿ of the hub 4^h of the control lever, and when button 8 is depressed the upper end 125 of spring 9 is moved against contact 12 and an electrical circuit is established in the usual manner. The push-button construc-

130

tion resembles an ordinary electric door bell push button, and does not require any screws for fastening the wire.

In the construction shown in Fig. 8 the 5 annular peripheral flange of base 2 and the cap piece 7 are omitted; and the button 8^x is made large enough to also serve as a cover for the underlying control levers. This button 8^x is centered by the flanges 8^a and 4^a on the 10 head and button respectively, as in Figs. 1 and 2, and headless screws 8^a are tapped through the lower portion of the wall of the button, and loosely engage relatively wide slots or grooves 4^s in the periphery of the 15 head 4^b of the upper control lever, as shown. In this case the horn button 8^x floats upon the lever 4. In both Figs. 1 and 2, and 8, the circuit closing devices are mounted upon the control levers, and the button can turn with 20 such lever.

Friction disks 15, such as shown in my above mentioned applications, may be provided being shown in Figs. 1, 2 and 8, to hold the levers in adjusted position; although any 25 suitable frictional devices may be used to hold the levers in adjusted position.

Any desired number of control tubes constructed as described can be nested and assembled within the fixed tube G; and the 30 steering wheel and wheel nut can be put in place over the ends of the control tubes and before the levers 4 are attached. The respective levers 4 can then be readily connected with their respective control tubes, as hereinbefore described.

The device can readily be disassembled when desired, or if it is necessary to remove the wheel this can be done without having to remove the tubes by detaching the control 40 levers from the tubes.

Obviously the number of control tubes and levers used may be varied according to the number of different controls which it is desired to have assembled at the center of the 45 steering wheel.

I do not herein claim the electric switch devices which will form the subject for a divisional application.

I claim:—

50 1. In a control assembly, a control tube provided with projecting lugs; a control lever arm having a head provided with a bore to receive the upper end of the tube, and with recesses in which the lugs are adapted to be seated; and means on the arm for holding the lugs in engagement with the recesses.

2. In combination with devices as set forth in claim 1,—a lever having an annular portion provided with notches adapted to be detachably engaged with the lever arm.

3. In a control assembly, a control tube provided with projecting lugs; a control lever arm having a head provided with a bore to receive the upper end of the tube and with recesses in which the lugs are adapted to be

seated; a retainer adapted to be secured to the head to retain the lugs in position in the recesses; and screws for attaching the retainer to the head.

4. In combination with devices as set forth in claim 3,—a lever having an annular portion provided with notches adapted to be detachably engaged with the lever arm. 70

5. In a control assembly, a control tube provided with projecting lugs; a control lever arm having a head provided with a bore to receive the upper end of the tube, and with slots in the bore corresponding in position with the lugs on the tube to permit the head to pass the tube and with recesses corresponding in position with the lugs on the tube and in which the lugs are adapted to be seated, and means on the arm for holding the lugs in engagement with the recesses. 75

6. In a control assembly, a control tube provided with projecting lugs; and a control lever arm having a head provided with a bore to receive the upper end of the tube, and with slots in the bore corresponding in position with the lugs on the tube to permit the head to pass the tube and with recesses in its face corresponding in position with the lugs on the tube and in which the lugs are adapted to be seated; a retainer adapted to be secured to the head to retain the lugs in position in the 80 recesses; and screws for attaching the retainer to the head. 85

7. In a control assembly a control tube provided with projecting lugs and slots above the lugs; a control lever arm having a head provided with a bore to receive the upper end of the tube; and with slots in the bore corresponding in position with the lugs on the tube and with recesses in its upper face corresponding in position with the lugs on the tube and in which recesses the lugs are adapted to be seated; a retainer adapted to be secured to the head to retain the lugs in position in the 90 recesses and provided with lugs engaging the slots in the tube above the lugs; and means for clamping the retainer to the head. 95

8. In combination with devices as set forth in claim 7,—a lever having an annular portion provided with notches adapted to be detachably engaged with the lever arm. 100

In testimony that I claim the foregoing as my own, I affix my signature.

DAVID E. ROSS.
